UNITED STATES PATENT OFFICE.

THEOPHILES LUCIER, OF DETROIT, MICHIGAN.

BOW-FACING OAR.

SPECIFICATION forming part of Letters Patent No. 611,497, dated September 27, 1898.

Application filed November 22, 1897. Serial No. 659,463. (No model.)

To all whom it may concern:

Be it known that I, THEOPHILES LUCIER, a citizen of the United States, residing at Detroit, in the county of Wayne and State of Michigan, have invented certain new and useful Improvements in Reverse-Stroke Oars, of which the following is a specification, reference being had therein to the accompanying drawings.

10 The invention consists in the peculiar construction, arrangement, and combination of parts, as more fully hereinafter described and claimed.

In the drawings, Figure 1 is a plan view of 15 a boat to which my oars are applied. Fig. 2 is a perspective view illustrating the connection between the handle and blade sections and the oar-lock. Fig. 3 is a horizontal section therethrough. Fig. 4 is a plan of the 20 blade-section.

A is the handle-section, and B is the blade-section, of my improved oar. The handle-section comprises the handle a, having a bifurcated stem or loom, preferably formed of 25 the separated bars b and b', secured to the handle at one end. The blade-section consists of the blade c and a bifurcated stem or loom, similarly formed to the handle-section of separated bars d d'.

30 C and C' are gear-segments secured, respectively, to the bifurcations of the handle and the blade sections, preferably by providing each segment with the sockets f, with which the ends of the bars b b' and d d' are 35 respectively engaged.

D is a frame in which the segments C and C' are pivotally secured, so as to be in mesh with each other, said frame thus forming a connection between the two sections of the 40 oar and also the oar-lock connection to the gunwale of the boat. The frame D is preferably formed of the two plates g and g', arranged parallel to each other on opposite sides of the segments and connected by the lugs h and h'. The lugs h extend across in the triangular spaces on opposite sides of the segments and the lugs h' in the spaces between the bifurcations of the oar and blade sections, respectively, beyond the pivot-pins i, in which 45 said segments are journaled.

In order to permit of the two sections of the oar being folded together, as shown in Fig. 3,

the sockets f, in which the bars b b' and d d' are secured, are arranged within the circle of the segments, so as to leave a space E between 55 the sections when folded together sufficient for the lugs h. The spokes or web connecting the rim and hub of each segment is also cut away on each side at F, so as to permit of the full stroke of the oar without interfering 60 with the lugs h'.

G are lugs or ears in the lower plate g', which are pivotally secured to ears H, secured to the gunwale of the boat.

In practice the oars thus constructed are secured, as described, to the boat. The oarsman may sit facing the bow of the boat, and by manipulating the oars in the usual way he will propel the boat in the forward direction.

The construction of my oar is designed to 70 secure at once strength, lightness, and simplicity. Thus the bifurcated stem or loom on each of the sections, in connection with a socketed segment secured thereto, forms a trussed structure which greatly increases the 75 strength of the oar. The frame D is also strengthened by the four points of connection between the plates g and g'. Both the frame and the segments may be formed of simple castings, the lugs h and h' being cast integral with the plates g and g', so as to match each other, and being bolted or otherwise secured together. The sockets f are also cast integral with the segments.

The bars b b' and d d' are preferably made 85 of separate pieces suitably spliced to the handle a and blade c, as shown in Figs. 3 and 4 of the drawings.

What I claim as my invention is—

1. In a reverse-stroke oar, an oar-section 90 comprising a gear-segment and a loom secured thereto consisting of separated bars secured to said segment at one end, connected to a single section at their opposite ends, in combination with a second oar-section provided with an intermeshing gear-segment, and means for securing the two sections together.

2. In a reverse-stroke oar, an oar-section 100 comprising a gear-segment having sockets formed thereon, and a loom consisting of separated bars engaging with said sockets at one end and connected to a single section at their opposite ends, in combination with a second,

oar-section provided with an intermeshing gear-segment, and means for securing the two sections together.

3. A reverse-stroke oar, comprising separate handle and blade sections bifurcated at their adjacent ends, intermeshing gear-segments secured to the bifurcations of said handle and blade sections respectively, and a connecting-frame to which said segments are pivotally secured adapted to be pivotally secured to the gunwale of the boat.

4. A reverse-stroke oar comprising separate handle and blade sections bifurcated at their adjacent ends, intermeshing gear-segments

secured to the bifurcations of said handle and blade sections respectively, and a connecting-frame to which said segments are pivotally secured comprising plates on opposite sides of said segments and connecting-lugs or cross-bars therefor extending between the bifurcation of said oar and blade sections.

In testimony whereof I affix my signature in presence of two witnesses.

THEOPHILES LUCIER.
